4 Claims.

(Cl. 88—15)

This invention relates to a design projecting device, the images projected thereby resembling those projected by a kaleidoscope, and it has for one of its objects the production of a means for projecting a colorful design or display upon a screen, background, sign-board, and the like, wherein a number of colorful, changing symmetrical designs may be displayed and produce a changing illuminated pattern for use in connection with illuminated signs.

Another object of this invention is the production of a simple and efficient projecting device for projecting a colorful design upon a screen or background, wherein a number of colorful changing symmetrical designs may be displayed for producing a colorful pattern in the nature of a background for extravaganza productions, borders for moving pictures, and the like.

A further object of this invention is the production of a simple and efficient colorful design projecting device wherein a number of design formations may be displayed for selection in producing rugs, linoleum, fabrics, and other patterns.

A still further object of this invention is the production of a simple and efficient design projecting device wherein movable colored transparent capsules, objects, or symmetrical bodies of regular shape are carried adjacent a fixed design so that the colored capsules, objects, or similar elements, may fall into many different positions, each position producing a different selective design of oval form.

Still another object of this invention is the production of a simple and efficient design projecting device wherein movable colored transparent capsules of regular shape and oval or rectangular in form are carried adjacent a fixed design so that the colored capsules or similar elements may fall into many different positions, each position producing a different selective design, and each of certain capsules containing a colored liquid in order to give a shaded effect when light is projected therethrough.

Another object of the invention is the production of a simple and efficient design projecting device where colorful objects including figures of flowers, men, women, animals and the like are carried on a design plate interposed between a light and fixed mirrors, the design plate being mounted in a rotatable housing which, when turned, produces a multiplicity of colorful designs.

Other objects and advantages of the present

invention will appear throughout the following specification and claims.

In the drawings:

Figure 1 is a side elevation of one form of the projecting device, certain parts being shown in section;

Figure 2 is a longitudinal sectional view taken on line 2—2 of Figure 1;

Figure 3 is an elevation looking at the front end of the device;

Figure 4 is a transverse sectional view taken on line 4—4 of Figure 1;

Figure 35 is a vertical sectional view taken on line 35—35 of Figure 34;

45 Figure 36 is a longitudinal sectional view showing the designoscope mounted within a further modified type of cabinet or housing;

Figure 37 is a front elevation of the cabinet shown in Figure 36, a certain portion being shown in section.

50 By referring to the drawings, it will be noted that the present invention preferably comprises in one form as shown in Figures 1 to 10, inclusive, an elongated tubular casing 10 carrying a light bulb of a conventional type 11, at its rear end, which bulb is electrically connected to a suitable connection through the medium of a conventional plug 12. The tubular casing 10 carries at its outer end a double convex lens 13 and suitable other lenses may be employed, such for instance, as the lights and lenses used in the projecting medium of moving pictures—when proper insulation will be installed, as occasion may require.

Longitudinally of the casing 10 is mounted a 65 mirror structure 14 which in the form shown, in Figures 1, 2 and 6, particularly comprises a pair of mirror plates 15 which are inclined toward each other along their top edges and spaced from each other at their bottom edges, their upper edges 70 being secured by means of suitable binding element 16. The lower edges of the mirror plates 15 are supported upon a base 17 which is preferably provided with a non-reflecting and light absorbing face 18. The mirror plates 15 have 75 mirror faces upon their inner faces which are

inclined in A-shaped formation. The mirror element 14 extends longitudinally of the casing 10 between the outer lens 13 and the tumbler supporting segment 19, which tumbler supporting segment 19 is preferably located near the rear 5 end of the casing 10 and adjacent the illuminating bulb or lighting device 11. The bulb 20 shown in Figure 2 may be either of ground glass or, if desired, clear glass, and a ground glass plate 21 may be located in front of the bulb 20, as shown 10 in Figure 2. The mirror element 14 is held in place by means of the anchoring fillers 22 which may be of any suitable or desired type to hold the mirror element 14 against shifting and in anchoring the mirror in place and shutting out 15 rays of light.

The casing 10 is preferably rotatably mounted within the supporting standards 23 so that the device may be easily supported upon a desk, table, or other support. These supports 23 preferably 20 encircle the casing 10 and beads or retaining rings 24 are carried by the casing between which the supporting standards 23 are mounted, thereby allowing the casing 10 to be easily rotated by the hand of the operator. The casing 10 may, if 25 desired, be fastened to a suitable stand and a suitable motor may be used for rotating the casing, such for instance as shown in Figures 19 to 26. The lower ends of the standards 23 are preferably diverged to provide supporting legs 25. 30 In this form, shown particularly in Figures 1 to 3 inclusive, the device may be utilized as a toy for projecting fanciful designs for the purpose of teaching children colors through the medium of projecting colorful and symmetrical designs upon 31 a screen or other background.

In connection with this invention, I preferably employ a particular type of tumbler segment which consists of a circular box-like member which fits snugly within the casing 10 and is suitably anchored therein. This tumbler segment 4 comprises a front plate 26, and a rear plate 27 arranged in spaced relation to provide a tumbler compartment 28 therebetween, and to permit a free tumbling movement of the tumblers within. These plates 26 and 27 are of transparent material such as glass, Celluloid, or the like, and when used in conjunction with moving picture machines, heat resistant glass is required.

It should be understood that any suitable lens might be used for projecting a desired effect, the well-known type of moving picture lens being adaptable for this purpose if desired. Here is required a great amount of light, thereby producing heat, and metal mirrors are preferably utilized since the mercury of ordinary mirrors evaporates.

A plurality of tumbler elements 29 in the nature of symmetrical bodies are located within the compartment 28 and each element 29 is selectively colored whereby a suitable design formation may be displayed in conjunction with a design plate or sheet 30 which is etched upon, secured to, or displayed upon the rear plate 27 in any suitable or desired manner. It should be borne in mind that the elements 29 are selectively colored and are transparent or sufficiently translucent to permit light cast from the bulb 20 to penetrate therethrough and to display the selected colors both of the elements 29 and the design sheet or plate 30 as light is projected therethrough. If desired, capsules or ampules may be used for the tumbler elements without departing from the spirit of the invention.

In conjunction with these elements 29, I may also employ a colored liquid, such as glycerin

and the like, indicated by the numeral 31 in the form shown in Figure 5. The elements 29 employed may be insoluble where liquid is used, to prevent the deterioration of the casing of the elements 29. The liquid may be of the same color as the element whereby different and varied shades of the same color may be projected, or it may be of a different color than the element to produce an entirely different color by the combination of the different colors of the element and the liquid. The elements are of conventional construction and if desired, the separable sections of the elements may be of different or of contrasting colors. A heavy liquid is preferably used in the elements.

Through the medium of the structure described, it should be understood that a very pleasing colorful and artistic design display may be produced of varying nature whereby the various designs may be displayed, and if desired may be assembled to produce an attractive pattern as will be hereinafter described.

The design may be supported upon the design plate 30 or may be directly carried thereby or applied thereto in any well-known manner. It may be appliquéd on, or may be incorporated in any way in the segment or on the plate, and may be blown into the glass, if desired.

In Figures 11 and 12 there are shown two distinct patterns which may be formed through the medium of the present device, but it should be understood that the type of design which may be displayed is almost limitless. The structure just described has been illustrated embodying two facing mirror strips inclined toward each other, although it should be noted that various forms of mirrors may be employed to multiply the designs in a manner such as illustrated in Figures 16, 17 and 18.

In Figure 13, a capsule is illustrated, one half of which is shown shaded for red, and the other half shown shaded for blue, wherein the sections of the capsule may be of different colors.

In Figure 16 there is shown a hexagonal arrangement of mirrors wherein the elements will be greatly multiplied. In Figure 17, three mirrors are illustrated producing five patterns, and in Figure 18, a mirror having five angular surfaces is illustrated, varying the design further.

If desired, as shown in Figure 14, the display device may be provided with a funnel-shaped screen support 32 which fits over the outer end of the casing 10, the outer flared end of the screen funnel 32 supporting an opaque screen 33 which will permit the image projected from the projecting device to be seen during the day time without the necessity of subduing the daylight. This is largely useful for the purpose of demonstrating the function of the device in the day time, particularly when making a sale. The opaque screen 33 may be of such translucent material as ground glass, Celoglass, or tracing paper, and if desired an extending collar or shield 33a may be added to the outer end of the funnel support 32 or any suitable extension provided to render the image on the screen 33 clearer in daylight.

Particular attention is invited to Figure 10 which illustrates the manner in which the device may be used as a toy for projecting a design upon a screen or background 34, the device being mounted upon a suitable table or other support 35. When the image is to be projected on the screen 34, the screen-supporting element or funnel 32 is removed from the outer end of the

casing 10 as will be obvious. It should be borne in mind, of course, that the casing 10 is mounted to rotate freely around the bulb and supporting socket therefor in the manner as indicated by the arrow in Figure 10, and the supports 23 may be easily snapped from or removed from the casing 10 when it is desired to support the device in the hand of the operator.

While the form described above is particularly adapted for a toy display device, although it may be used for other purposes, the device or form described in the following is particularly adapted for display for commercial purposes and for displaying a multiplicity of designs producing pictorial colorful patterns to attract the vision of the observer. In the form shown in Figures 19 and 20, a suitable supporting housing 40 is illustrated carrying a suitable sign and border 41, and the display device is preferably mounted within the housing 40 and comprises a light box 42 20 preferably circular in formation, carrying lights 43. A plurality of projecting tubes 44 are supported upon a circular support 45 in regular spaced relation around the periphery thereof, and are carried by supporting cradle elements 46 25 forming bearings or supports for the projection tubes 44. A friction driving belt 47 extends around and contacts with all of the projection tubes 44 engaging the outer faces, as shown in Figures 19 and 20, and the belt may be roughened if desired, to provide a more efficient friction contact. Friction driving rollers 48 are mounted in a position to contact with the endless driving belt 47 and these rollers are driven by a suitable driving means, such as a motor 49.

In the form shown in Figures 19 and 20, the projection devices 44 are each provided with a suitable design display mechanism, such as is described in connection with Figures 1 and 2, and such as is illustrated in detail in Figures 7 and 8 40 to provide a series of changeable colorful designs to produce a border pattern around a sign display within the pattern so formed.

The individual projection device 44a may be individually driven, if desired, through separate 45 motors 49a without departing from the spirit of the invention.

In Figure 22 there is shown a further modified form of the invention to that as shown in Figures 19 and 20, wherein a display sign 50 is mounted upon a housing 51 and a plurality of projection devices 44a are mounted in the form of a circle to project a pictorial border display around the edge of the sign 50. The projection devices 44a are rotatably mounted within the bearings 52, 55 and these projection devices are driven through a driving gear 53 which meshes with the gears 54 carried by the projection devices 44a.

In Figures 24 and 25 there is shown a further modified form of the invention wherein a battery 60 of projection devices 55 are arranged in horizontal alignment and are driven by an endless belt 56 passing thereover from a drive pulley 57 actuated by a motor 58. The device may be suitably mounted upon a support 59. In this form, 65 the device may be adapted for displaying a fanciful series of designs to produce a pictorial and attractive background of a highly colorful and changing nature particularly adapted for use in extravaganza productions wherein a very attractive background may be thrown upon a stage or back-drop thereof.

In the structure shown in Figures 19, 20, 22, and 24, a suitable boxed-in housing may be provided to shield the apparatus from external light 75

and cause the projection devices to project the lighted image upon the sign and border 41 which may be formed of parchment, or other translucent material. In the form shown in Figures 24 and 25 where the device is used for projecting designs upon a background such as a curtain drop, the device may be used without the front panel, such as is indicated by the numeral 85a in Figure 4.

10 In Figure 27, there is shown a modified form of the invention wherein the numeral 85 indicates a kaleidoscope casing within one end of which is placed an electric light 86 and a reflector 87. The casing 85 is preferably of an elongated tubular character within which is supported and anchored an elongated reflecting mirror 88 of the general type illustrated in Figure 6 but tapering toward its outer end. An adjustable lens-carrying cap 89 is slidably mounted upon the outer end of the casing 85 to facilitate focusing. A suitable kaleidoscope tumbler element 70 is supported between the mirror 88 and the light 86. By utilizing the tapering mirrors, the size of the image is increased.

25 It should be understood that if desired, a suitable packing or filler 71 may be mounted within the casing 10 between the wall of the casing and the mirror element 14, as shown in Figure 4.

As shown in Figure 28, the numeral 75 indicates 30 a metallic mirror element which may be substituted for the glass mirror element such as is shown in Figure 4. As shown in Figure 29, the tumbler element may consist of a capsule-like or symmetrical body 76 which may be formed of 35 glass or other transparent or translucent material having a Cellophane or other colored lining, 77. This tumbler element may constitute an open-ended glass tube upon the inner face of which may be securely fastened a piece of colored 40 Cellophane secured by means of Duco glue.

45 In Figures 30 and 31 a further modified form is shown of a tumbler element which consists of a body of heat resisting glass such as Pyrex glass comprising a body 78 having a cavity 79 terminating around its edge in a bevelled face 80 upon which fits a bevelled closure segment 81 which may be cemented or suitably fastened.

50 In applying the invention as defined particularly in Figures 19 to 26, inclusive, it will be obvious that the design of the display may be easily changed without the necessity of entirely reconstructing the display sign as is now necessary in connection with certain electrical signs. A mere turn of the cylinders displaying the 55 pictorial display will change the display effect and design projected upon the screen or display surface. The device such as illustrated in Figures 19 to 26 may be timed so that at certain intervals the projected design may be changed merely by 60 momentarily halting the movement of the driving means, such for instance, as the motor for rotating the various projection devices.

65 In the form shown in Figure 32 an elongated conical tube 82 is provided, which tapers toward its outer end, and longitudinally extending triangularly arranged mirrors 83 are mounted within the tube 82 in the manner shown in Figure 33. These mirrors 83 have their mirrored faces facing each other in the same manner as described with 70 respect to the other types of structure illustrated in the foregoing figures. A suitable filler 84 is interposed between the mirrors 83 and the tube 82. A lens 85 is carried in the outer end of the tube 82 at the outer end of the mirrors 83 and a tumbler housing 86 abuts against the inner

edges of the mirrors 83. A disc 87 of ground glass, and the like, rests against the outer face of the tumbler housing or tumbler-supporting segment. A transparent disc 88 of glass carrying a permanent design fits against the disc 87, 8 and a spring-retaining ring 89 frictionally engages the inner face of the tube 82, and the outer face of the disc 88, thereby holding the parts in place. A light bulb 90 is carried by a cap 91 and fits into the inner end of the tube 82, 10 the cap fitting over the inner end of the tube 82 as shown in Figure 32.

The tube 82 is rotatably mounted within the supports 92, as shown in Figure 32, and an outwardly flared light-shielding funnel 93 projects 15 outwardly beyond the outer end of the tube 82. A translucent sheet or plate 94 is carried by the outer end of the funnel, upon which the changeable design may be cast when projected through the mirrors 83 and lens 85. This form shown in 20 Figures 32 and 33 will provide a very entertaining, and amusing toy which may be produced at a minimum expense.

25 In Figure 34 there is shown a structure wherein a housing 95 is illustrated carrying a translucent display screen sheet or plate 96 at its outer end. A projection device 97 is mounted within the housing 95 upon a base 98. The projection device 97 comprises a rotatable tube 99 rotatably mounted within the support 100 carried by the 30 base 98. A driving belt 101 passes around the tube 99 and is driven by a motor 102 mounted upon the base 98. A collar 103 is fitted in the inner end of the tube 99 and rotates therewith, the collar 103 being enlarged at its rear end, as 35 at 104, to loosely fit over the projecting neck 105 of the lamp housing 106. A suitable lamp 107 is carried within the housing 106 and a reflector 108 is located behind the lamp 107. The tube 99 carries triangularly arranged mirrors 109 similar 40 to the mirrors previously described.

45 A tumbler housing 110 of the type previously illustrated and described together with the permanent design plate 111 and the retaining ring 112 are mounted in the collar 103 so as to rotate 50 with the collar 104 and tube 99. In the form shown in Figures 34 and 35, the tube 99 is journaled upon the support 100 and neck 105 and the image is projected upon the display screen 96 to be viewed from the outside.

55 In the form shown in Figures 36 and 37, a cabinet 115 is provided which supports a screen 116 at its outer end having an advertising border 117 formed around the edge thereof. A shield housing 118 is located within the cabinet 115 in line with the inner edge of the border and a projection device 119 of the type illustrated and described with respect to Figures 34 and 35 is mounted within the housing 118. The projection device 119 is driven by means of a motor 120 and belt 121. A translucent screen 122 is formed within the border 117 in a position to display the image projected thereon by the projection device 119. Lights 123 are mounted at the rear end of the cabinet 115. This form of device is 60 designed particularly for advertising display.

65 It should be understood that the designs are controllable by starting and stopping the rotation of the projection devices, and the present device is particularly adaptable for projecting 70 colorful design displays upon a screen to display various design forms and when an attractive form of design is produced, the rotation of the projection device may be stopped and that particular design displayed may be photographed in order 75

that it may be retained. This may be done either by photographing the image cast upon the screen, or by projecting the design directly into the lens of the camera. In this way, the design formed 5 may be preserved without the necessity of depending upon the creative ability of a draftsman or other designer.

It should be understood that certain changes in the mechanical construction, combination and 10 arrangement of parts may be employed without departing from the spirit of the invention so long as such changes fall within the scope of the appended claims.

Having described the invention, what is claimed 15 as new is:

1. As an article of manufacture, a design-forming device for use in connection with a projection machine of the character described comprising a design-forming casing mounted for rotatable 20 movement, said casing having a plurality of spaced transparent plates providing a tumbler-receiving compartment, a regularly formed definitely fixed design carried by one of the transparent plates, and a plurality of regularly formed 25 differently colored transparent tumbler elements freely movable within the tumbler-receiving compartment and adapted to form well-balanced regular and varied symmetrical designs when the casing is revolved and a beam of light is projected 30 therethrough.

2. As an article of manufacture, a design-forming device for use in connection with a projection machine of the character described comprising a design-forming casing mounted for rotatable 35 movement, said casing having a plurality of spaced transparent plates providing a tumbler-receiving compartment, a regularly formed definitely fixed design carried by one of the transparent plates, a plurality of regularly formed 40 differently colored transparent tumbler elements freely movable within the tumbler-receiving compartment and adapted to form well-balanced regular and varied symmetrical designs when the casing is revolved and a beam of light is projected 45 therethrough, each tumbler element comprising a hollow body and being partly filled with

liquid which is adapted to flow and spread over the inner face of the tumbler elements as the tumbler elements move end over end as the design-forming casing is rotated to display colors of varying and slowly moving density when a beam of light is projected therethrough.

3. As an article of manufacture, a design-forming device for use in connection with a projection machine of the character described comprising a design-forming casing mounted for rotatable 10 movement, said casing having a plurality of spaced transparent plates providing a tumbler-receiving compartment, a regularly formed definitely fixed design carried by one of the transparent plates, a plurality of regularly formed 15 differently colored transparent tumbler elements freely movable within the tumbler-receiving compartment and adapted to form well-balanced regular and varied symmetrical designs when the casing is revolved and a beam of light is projected 20 therethrough, each tumbler element comprising a hollow body and being partly filled with liquid of heavy volume which is adapted to slowly flow and spread over the inner face of the tumbler elements as the tumbler elements move end over 25 end as the design-forming casing is rotated to display colors of varying and slowly moving density when a beam of light is projected therethrough.

4. As an article of manufacture, a design-forming device for use in connection with a projection machine of the character described comprising a design-forming casing mounted for rotatable movement, said casing having a plurality of spaced transparent plates providing a tumbler-receiving compartment, a regularly formed definitely fixed design carried by one of the transparent plates, and a plurality of tubular-like 35 differently colored transparent tumbler elements freely movable within the tumbler-receiving compartment and adapted to form well-balanced regular and varied symmetrical designs when the casing is revolved and a beam of light is projected 40 therethrough.

WILLIAM O. WETMORE.
